UNITED STATES PATENT OFFICE.

LAMBERT SNYDER, OF ROCHELLE PARK, NEW JERSEY.

ACETYLENE-GAS GENERATOR.

SPECIFICATION forming part of Letters Patent No. 738,855, dated September 15, 1903.

Application filed May 6, 1901. Serial No. 58,904. (No model.)

To all whom it may concern:

Be it known that I, LAMBERT SNYDER, residing at Rochelle Park, State of New Jersey, have invented certain new and useful Improvements in Mechanisms for Feeding Carbid or Like Substances in Gas-Generators, of which the following is a specification, illustrated by the accompanying drawings.

The improvement is particularly related to gas-generators wherein powdered or lump carbid is carried in a receptacle which has a discharge-opening, through which the carbid is discharged little by little, as required, by tipping or inverting the receptacle.

The nature of the improvements will be clearly understood from the preferred form of the invention shown in the accompanying drawings, wherein—

Figure 1 is a plan view of one embodiment of the invention; Fig. 2, a partial side elevation of the same; Fig. 3, a central vertical section through the carbid-receptacle; Fig. 4, a horizontal section centrally through the receptacle, and Figs. 5 and 6 a face view and a section of the feeding-opening of the receptacle.

As the improvement relates particularly to carbid-feeding mechanisms and does not especially concern the other well-known attachments for acetylene-generators and the like, the description will be limited to the novel features.

The generator-casing 1 may be of any desired type, preferably surmounted with a shell or chamber 4, which has a carbid-receptacle 5 mounted within it. The carbid-receptacle is mounted to turn upon an axis, as shown, one end being preferably provided with a trunnion 6 and the other with a shaft 7, which extends through a suitably-tight joint in the casing 4 and carries a ratchet-wheel 8 outside of the casing. The ratchet-wheel 8 is turned by means of an operating-lever 9 and pawl 10. The operating-lever 9 may be controlled by the gasometer 3, as shown, if a satisfactory gasometer be used; but of course the invention is not limited to a separate gasometer, it being only necessary to cause the gas generated to actuate the feed mechanism by a suitable connection, as is common in acetylene-generators. The carbid-receptacle 5 has a discharge-opening 12 and a pointed

feed-lip 13. This feed-lip 13 serves to prevent a sudden discharge of a large quantity of the carbid, because as the receptacle is inverted to feed, as shown in Fig. 3, the carbid will gradually begin to pour at each side of the point of the lip 13 instead of pouring freely out of the entire width of the opening 12. As will be seen from Fig. 3, the weight of the carbid tends to rotate the receptacle in a direction to raise the feed-opening 12 and stop the feeding. In order to prevent too wide a range of movement of the lever 9 in feeding the carbid from the receptacle, a second pawl 15, pivotally secured to the casing 4 by a pin-and-slot connection, as shown, is employed. The slot is not absolutely necessary, but it permits the turning backward of the ratchet 8 for a greater distance than would be possible if the slot were not present. The pawl 15, limiting as it does the backward turning of the carbid-receptacle, enables the pawl 10 to pass successive teeth of the ratchet 8 from time to time as the receptacle is gradually emptied. The lever 9 is weighted at its left-hand end, so as to cause it to follow within limits the motions of the gasometer-bell 3.

An arrow-head or other marker on the ratchet 8, corresponding in angular position to the opening 12, enables the operator to tell how far the carbid-receptacle has been emptied, because it indicates the position of the discharge-opening 12. For refilling, a charging cover 16 is provided in the top of the casing 4. When the receptacle is empty, it may be turned until the arrow points toward the charging-cover 16, and then the cover may be removed and the charge inserted through into the receptacle 5 through its opening 12.

From the foregoing it will be seen that my invention comprises mechanical means for turning the holder in one direction to cause feeding as it is required from time to time and means for limiting the backward movement of the holder in the reverse direction.

I do not mean to restrict myself to the precise form of mechanical elements employed for accomplishing either of these functions.

I do not herein claim, broadly, the pivotally-mounted carbid-holder shown and described and claimed in the copending application of Charles Goodyear, Serial No. 58,881, filed May

6, 1901, for "Mechanism for feeding carbid or other substances in gas-generators."

What I claim, therefore, and desire to secure by Letters Patent, are the following features, to wit:

- 5 1. In a gas-generator, the combination of a pivotally-mounted carbid-holder, a discharge-opening provided with a pointed feed-lip serving to prevent a sudden discharge of a large quantity of carbid, and operative connections for automatically inverting said holder, for substantially the purposes set forth.
- 10 2. In a gas-generator, the combination of a pivotally-mounted carbid-holder having a discharge-opening, an operating-lever con-

nected to rotate the holder in a direction to feed the carbid through the discharge-opening, the weight of the carbid tending to rotate the holder in a direction to raise the discharge-opening and stop the feed, and means 20 for permitting a limited rotation of the holder under the weight of the carbid in a direction to raise the discharge-opening, for substantially the purposes set forth.

Signed this 4th day of May, 1901, at New York, N. Y.

LAMBERT SNYDER.
